ATTORNEY

UNITED STATES PATENT OFFICE.

ELIZABETH GLADWIN BOUTON, OF PITTSFIELD, MASSACHUSETTS.

ORANGE-PULP REMOVER.

SPECIFICATION forming part of Letters Patent No. 562,372, dated June 23, 1896.

Application filed June 6, 1895. Serial No. 551,831. (No model.)

To all whom it may concern:

Be it known that I, ELIZABETH GLADWIN BOUTON, a citizen of the United States, and a resident of Pittsfield, county of Berkshire, 5 and State of Massachusetts, have invented certain new and useful Improvements in Orange-Pulp Removers, of which the following is a specification, reference being had to the accompanying drawings, forming a part thereof, in which similar letters of reference indicate corresponding parts.

My invention relates to certain new and useful improvements in devices for extracting the pulp from oranges and other fruit; and 15 its object is to provide a simple, effective, and inexpensive device by means of which the pulp of an orange may be entirely removed from the skin, and finally divided or separated.

With this and other objects in view the invention consists of the annular base-plate adapted to be placed upon a cup or other receptacle, and a semispherical body mounted upon said base-plate, and provided with a 25 number of vertical slits or slots forming wings, the edges of which are sharp and adapted to cut the pulp of the orange.

The invention is fully disclosed in the following specification, of which the accompanying drawings form a part, and in which—

Figure 1 is a plan view of my improved device; and Fig. 2 is a transverse section thereof, showing also the method of connecting the same with a cup or other vessel.

In the practice of my invention, I employ 35 an annular base-plate A, provided with an annular depending flange or rim a, and an upwardly-directed annular flange or rim a', and I also, preferably, employ a second annular 40 depending flange or rim a², which, in connection with the depending flange or rim a, forms an annular cavity adapted to receive the upper portion of a cup or other receptacle B. The annular plate A is also provided, at its 45 inner edge, with an upwardly-directed flange C, between which and the outer edge of the plate, and preferably between the upwardly-directed flange C and the depending flange or rim a², is formed a row of perforations or openings D.

Mounted upon the annular base-plate A, and surrounding the flange C, is a substantially semispherical body D', which is pro-

vided with a series of vertical slits or slots E, forming wings or plates F. These slits or 55 slots E are cut diagonally with relation to the diameter of the semispherical body, so that the wings formed thereby are provided with sharp cutting edges and said wings also project at an angle, as above described, to the 60 diameter of the semispherical body.

In practice an orange or other fruit is preferably cut in half and the pulp of each part is removed by simply forcing the part down upon the spherical body and turning the part 65 of the orange so that the cutting edges of the wings will cut out the pulp from the skin, and this operation is continued until all the pulp has been removed.

It will be observed that by this device the 70 pulp is not only removed from the skin, but furthermore it is cut up and divided into finely-separated particles which fall into the cup, or is collected around the base of the semispherical body, while the juice of the orange 75 passes into the cup.

The device may be made of metal, glass, or other desirable material and can also be constructed in various shapes which will all fall within the spirit and scope of the invention. 80

Having thus fully described my invention, what I claim as new, and desire to secure by Letters Patent, is—

The combination of a base A having an annular depending rim a, an upwardly-projecting flange a', a second depending rim a² forming with the rim a an annular cavity, an upwardly-directed flange C, said base A being provided with a row of perforations between the flanges a' and C, a substantially semispherical body D mounted on the base surrounding the flange C, said body being provided with a series of vertical slits E, cut diagonally with relation to the diameter of the body and forming overlapping wings F, the edges of said wings being sharp and within the circumferential plane of the body, substantially as described. 85 90 95

In testimony that I claim the foregoing as my invention I have signed my name, in presence of the subscribing witnesses, this 21st day of May, 1895.

ELIZABETH GLADWIN BOUTON.
